TYPEWRITER CARRIAGE RETRCTOR
DEVICE

Sifas R. Dague, Wichita, Kans.

Application May 7, 1945, Serial No. 592,458

4 Claims. (Cl. 197—65)

1

My invention relates to an improvement in typewriter carriage retractor devices and has for its object to provide a device of the kind mentioned that can be attached in its entirety to any standard typewriter so that the typewriter may be moved from place to place and the carriage retractor will go with it and remain in perfect adjusted working position.

Another object of the invention is to provide a device of the kind mentioned that will retract the typewriter carriage and also operate the line spacing lever to revolve the typewriter roll as is normally done by hand.

A further object is to provide a device of the kind mentioned that is simple, inexpensive to make and sell, as well as one that is durable and long lived.

A still further object is to provide a device of the kind mentioned that is operable by either hand of the operator and may be operated with less movement of the operating hand than is now required to retract the carriage and space the typed lines.

A still further object is to provide a device of the kind mentioned which is operated by vertical movements of the operator's hand, thereby taking advantage of the force of gravity to assist in operating the device which in turn eases the operation of the device and the job to be done. These and other objects will be more fully described as this description progresses.

Now referring to the accompanying drawings:

Fig. 1 is a detail front view of a typewriter showing my typewriter carriage retractor device applied thereto.

Fig. 2 is a detail plan view of the device shown in Fig. 1.

Fig. 3 is an enlarged detail sectional view of the spacing lever standard that is attachable to the spacing lever of the typewriter.

Fig. 4 is a detail sectional view through the bearing block that supports the typewriter carriage retractor device, the view being taken along the line IV—IV in Fig. 5.

Fig. 5 is an enlarged detail side view of the bearing block that supports the typewriter carriage retractor device on the typewriter.

Fig. 6 is a front view of a typewriter showing a modified form of the typewriter carriage retractor device applied thereto.

Fig. 7 is a top plan view of the device shown in Fig. 6.

Fig. 8 is a top plan view of a typewriter showing still another modified form of the typewriter carriage retractor device applied thereto.

2

Fig. 9 is a top plan view of the device shown in Fig. 8.

Fig. 10 is an enlarged detail top plan view of the ratchet engaging mechanism employed in the form of the invention shown in Figures 8 and 9.

Fig. 11 is a detail front view of the device shown in Fig. 10, the view being taken along the line XI—XI in Fig. 9 and looking in the direction of the arrows.

10 Similar numerals of reference designate the same parts throughout the several figures of the drawings.

In the drawings is shown the outline of any standard typewriter A, which has a platen or roll 12 that is rotatably operable by a lever, in steps, by the side way movement in the direction of the arrow b of a spacing lever 13, also the continued movement of the lever 13 in the direction of the arrow b will move or retract the typewriter carriage and roll 12 therein from left to right preparatory for typing a new line. The typewriter is provided with a lower frame element 14 that surrounds the keyboard area c. It is the frame element 14 to which my improved typewriter carriage retractor device is attached and supported thereby.

The spacer and retractor device comprises, as shown in Figures 1, 2, 3, 4 and 5, a combination bearing and clamp element consisting of a bearing block 15 which has a curved or hooked top portion 16 that is designed to overlap the top edge of the typewriter frame 14 to increase the solidity and stability of the bearing block 15 on the typewriter frame 14. The lower portion of the bearing block extends below the journal portion of the bearing and also extends below the lower edge of the frame member 14 of the typewriter. Positioned against the inside of the typewriter frame 14 and a portion of which extends below the typewriter frame 14 is an L-shaped clamp block 18, the foot 18a of the L, resting against the lower portion of the bearing block 15, and bolts 19 pass through the lower portion of the bearing block 15 and the clamp block 18, and below the frame 14 of the typewriter, and nuts 20 threaded on the bolts 19 serve to pull the bearing block 15 and the clamp block 18 toward each other to rigidly bind them on the typewriter frame 14.

Revolvably carried in the journal 17 is a shaft 21, and rigidly mounted on the shaft 21 is a pair of collars, 22 and 23, said collars being positioned, one on either side of the journal bearing 17 to prevent longitudinal movements of the shaft 21 in the journal 17. One end of the shaft 21 is bent to form a lever 21a, that extends across the front of

the typewriter and normally stands in parallelism with the front cross member of the typewriter 14 as illustrated by the dotted lines 21x.

On the outer end of the lever 21 is a standard 24 that projects upwardly therefrom and on the upper end of which is rigidly mounted a ball 25. It will be understood that something other than a ball may be substituted for the ball, for example—a short bar.

When the lever 21a is in its normal position 21x, 10 the ball 25 is positioned in the center of the typewriter between the letter keys B and N of the typewriter. The other end of the shaft 21 is bent upwardly to form a lever portion 21b, and is bent at the point C, for purposes that will later be described.

The upper end of the lever 21b is turned rearwardly at a point above the typewriter spacing lever to form a shaft 26 that is in parallelism with the shaft 21.

On the shaft 26 is revolvably mounted a spool 27 that rests against a standard 28 that is rigidly mounted on the typewriter spacing lever 13. The standard 28 is a straight shaft, the lower end of which is split longitudinally as at 28a and at the lower end of the split 28a is formed a seat 28b that is adapted to receive the shifting lever 13 and a screw 29 passes through the two lower portions of the split portion of the standard 28 and serves to rigidly bind and hold the standard 28 on the shifting lever 13.

The lever 21a and knob 25 thereon are heavy enough to overbalance the lever 21b and spool 27 so the spool 27 will always rest against the standard 28 as the typewriter carriage travels across the machine as the typing is being done. When the typed line has been completed, the carriage and roll 12 will have travelled from right to left across the machine and the levers 21a and 21b will be in the dotted positions 21x and 21x', whereupon the heel of either hand of the typist may be placed on the knob 25 and pressed downwardly whereupon the spool 27 will push against the standard 28 to retract the typewriter carriage and roll 12 from left to right across the machine and also swing the spacing lever 13 to the right to revolve the roll 12 to move the paper on which the typing is being done one space preparatory for writing a new line, the same as would normally be done by hand if the retractor device were not on the machine.

If it is desired to revolve the typewriter roll 12 for line spacing without retracting the carriage, this may be done by a quick short stroke of the heel of either hand of the typist on the knob 25. Spacing of the paper being typed on, may be accomplished in the manner above described while the carriage of the machine is in any position, either extreme or intermediate, the extreme positions.

In Figures 6 and 7 is shown a modification of the retractor device, the difference being that the standard 28 and spool 27 and shaft 26 are omitted and a link 30 is substituted therefore. One end of the link 30 is bent at right angles to the link 30 and is pivotally mounted on the upper end of the lever arm 21f and is swingable about an axis that is in parallelism with the axis of the typewriter roll 12 when the typewriter carriage is in its central position on the typewriter. The other end of the link 30 is provided with an eye formation 31 in which is loosely positioned the outer end of the shifting lever 13 of the typewriter.

The lever 21f is curved similar to the reverse of the letter S, and curve G of the lever 21f being

provided to give an open view space so that copy may be laid at the left side of the typewriter and when the lever 21f is in its extreme left position, it will not be in the line of view of the typist looking at the copy.

In Figures 6 and 7, the shaft 21 may have either the lever 21a and ball 25, or the lever and handle as shown in Figures 8 and 9, which will later be described.

As shown in Fig. 6, when the lever 21f swings, the upper end of the lever 21f travels in an arc, but the shifting lever 13 travels in a straight horizontal line, therefore as the typewriter carriage and lever 21f move, the pivotal connection 30a of the link 30 to the lever 21f will permit the other end of the link 30 to travel in a straight line while the end of the lever 21f travels in an arc, and the eye 31 will revolve on the shifting lever 13 as the link 30 turns with the arcuate travel of the upper end of the lever 21f.

The operation of the device above described and shown in Figures 6 and 7 is the same as that described for Figures 1 and 2.

In Figures 8, 9, 10 and 11 is shown still another modification of the typewriter carriage retractor device. The particular object of this device is the same as the others above described and in addition thereto to provide a device of the kind mentioned in which the operating lever 21g remains stationary in its normal position before the typewriter front cross frame 14 during the travel of the typewriter carriage and roll 12 across the machine as the line is typed, yet at any point of the travel of the typewriter carriage and roll 12, the lever 21g may be pressed downwardly to retract the carriage or rotate the roll 12 for line spacing and the retractor device will come into engagement immediately to retract the carriage for a part of a line or to rotate the roll 12 for line spacing without pressing the lever 21g down to its extreme position as indicated by the dotted lines 21h.

As shown in Figures 8 and 9, the lever 21g is provided with a handle element 32 that may be slipped on the lever 21g from the position shown in full lines, see Fig. 9, to the dotted position 32a. This adjustment is provided so the handle 32 may be conveniently positioned for a right handed or left handed person using the retractor device. The handle is frictionally held in its adjusted position on the lever 21g by any one of numerous devices in which there is no invention, therefore the details of the device are not shown or further described.

In the retractor device shown in Figures 8 and 9, the shaft 21 is cut in two at the point 33, and the other portion 21j of the shaft 21 is carried in a bearing block 34 having similar construction to that shown in Fig. 4, and as is shown in Fig. 11.

The shaft 21j is bent at the point 35 to form the upwardly directed lever 21i. One end of a link 36 is pivotally connected to the upper end of the lever 21i at the point 37, and the other end of the link 36 is universally connected to a fitting 38 at the point 39, the fitting 38 being rigidly mounted on the spacing lever 13 of the typewriter as shown.

On the inner end of the shaft 21j is rigidly mounted a ratchet segment 40, and on the inner end of the shaft 21j is rigidly mounted a lever arm 41.

On the outer end of the lever arm 41 is pivotally mounted a ratchet pawl 42 that is adapted to engage the ratchet segment 40 so as to move the ratchet segment 40 with the lever

arm 41 as the lever arm is swung from left to right.

The ratchet pawl 42 is provided with an adjusting arm 43 in which is threadedly carried an adjusting screw 44, the lower end of which is adapted to engage or rest on a support element 45, the inner end of which rests against the typewriter frame 14 and is rigidly held in position between the frame 14 and the bearing block 34 by means of the bolt 46.

A helical spring 47 is positioned around the shaft 21 with one end of the spring bearing on the typewriter frame 14 and the other end of the spring 47 being connected with the shaft 21, the spring being tensioned to hold the lever arm 21g in its normal position before the typewriter as indicated by the dotted lines 217 and which also holds the lever arm 41 in its normal position shown by the dotted lines 41a, and when the lever arm 41 is in its normal position 41a, the end of the adjusting screw 44 will rest on the support 45 and hold the ratchet pawl 42 in a raised position so it is out of engagement with the ratchet segment 40.

The operation of the device as shown in Figures 8, 9, 10 and 11, is as follows: As the typing is being done the typewriter carriage and roll 12 therein will move from right to left and with it will move the lever 21i from the dotted position 21m to the dotted position 21n, and similarly the ratchet segment will move from its dotted position 40a to the dotted position 40b, and during this movement the levers 21g and 41 will remain inactive. Now if the roll 12 is to be revolved to space a typing line, or the carriage and roll are to be retracted at any point between the dotted position 21m and 21n the lever 21g may be pressed downwardly, whereupon the lever 41 will be swung to the right and immediately upon its starting to move, the adjusting screw 43 will disengage the support arm 45 and the ratchet pawl 42 will fall into engagement with one of the ratchet teeth of the ratchet segment 40, whereupon the shafts 21 and 21j will revolve together to operate the spacing lever 13 of the typewriter to space a typing line or to retract the carriage. This arrangement makes it possible to do line spacing or carriage retracting at any point intermediate the extreme positions of the carriage without dropping the hand of the typist to some lowered position of the lever 21g, such as the position shown in the full lines of the lever 21g in Fig. 8. Upon the completion of the spacing or retracting of the carriage, either in part or as a whole, the lever 21g will be returned to its normal position 21i by the spring 47 upon the release of the handle 32 by the hand of the typist.

Such modifications of my invention may be employed as lie within the scope of the appended claims without departing from the spirit and intention of the invention.

Now having fully shown and described my invention, what I claim is:

1. In a typewriter carriage retractor and line spacing lever operating device of the kind described; the combination of a lever positioned in front of the keyboard of a typewriter, a shaft, said shaft being revolvably carried in bearing means that is detachably attached to the left side frame of the typewriter and holds the shaft in close proximity to and in parallelism with the said frame, said lever being carried by one end of said shaft, a second lever, said second lever being carried on the other end of the said shaft, said second lever having a bend therein where-

by the lower end of the second said lever may assume a carriage retracting position substantially parallel with the vertical side of the typewriter side frame and the upper end of the second said lever will be positioned at a point between the sides of the typewriter, and means intermediate the upper end of the second said lever and the typewriting spacing lever for engagement therewith to operate the said spacing lever and to retract the typewriter carriage.

2. In a typewriter carriage retractor and line spacing lever operating device of the kind described; the combination of a lever positioned in front of the keyboard of a typewriter, a shaft, said shaft being revolvably carried in bearing means that is detachably attached to the left side frame of the typewriter and holds the shaft in close proximity to and in parallelism with the said frame, said lever being carried by one end of said shaft, a second lever, said second lever being carried on the other end of the said shaft, said second lever having a bend therein whereby the lower end of the second said lever may assume a carriage retracting position substantially parallel with the vertical side of the typewriter side frame and the upper end of the second said lever will be positioned at a point between the sides of the typewriter, and means intermediate the upper end of the second said lever and the typewriting spacing lever for engagement therewith to operate the said spacing lever and to retract the typewriter carriage, said means intermediate the upper end of the second said lever and the typewriter spacing lever being a standard, one end of said standard having clamp means formed therein, the outer end of said spacing lever being rigidly held in said clamp means and supporting the standard in a vertical position, and the second said lever having a roller thereon and bearing against the said standard for operation of the spacing lever.

3. In a typewriter carriage retractor and line spacing lever operating device of the kind described; the combination of a lever positioned in front of the keyboard of a typewriter, a shaft, said shaft being revolvably carried in bearing means that is detachably attached to the left side frame of the typewriter and holds the shaft in close proximity to and in parallelism with the said frame, said lever being carried by one end of said shaft, a second lever, said second lever being carried on the other end of the said shaft, said second lever having a bend therein whereby the lower end of the second said lever may assume a carriage retracting position substantially parallel with the vertical side of the typewriter side frame and the upper end of the second said lever will be positioned at a point between the sides of the typewriter, and means intermediate the upper end of the second said lever and the typewriting spacing lever for engagement therewith to operate the said spacing lever and to retract the typewriter carriage, said means intermediate the upper end of the second said lever and the typewriter spacing lever being a link, said link having a right angle turn at one end thereof, said turned link end being journaled in a bearing carried on the upper end of the second said shaft, said link having an eye formation on the other end thereof, and said spacing lever being loosely held in said eye.

4. In a typewriter carriage retractor and line spacing lever operating device of the kind described; the combination of a lever positioned in front of the keyboard of a typewriter, a shaft,

said shaft being revolvably carried in bearing means that is detachably attached to the left side frame of the typewriter and holds the shaft in close proximity to and in parallelism with the said frame, said lever being carried by one end of said shaft, a second lever, said second lever being carried on the other end of the said shaft, said second lever having a bend therein whereby the lower end of the second said lever may assume a carriage retracting position substantially parallel with the vertical side of the typewriter side frame and the upper end of the second said lever will be positioned at a point between the sides of the typewriter, and means intermediate the upper end of the second said lever and the typewriting spacing lever for engagement therewith to operate the said spacing lever and to retract the typewriter carriage, said shaft being made in two sections, said sections being positioned in axial alignment with each other, and clutch means carried by the adjacent ends of said shaft

sections whereby the second said lever will travel with the typewriter carriage and the first said lever may stand still, and upon the downward movement of the first said lever the clutch means engages to drive the second said lever to retract the typewriter carriage.
